UNITED STATES PATENT OFFICE.

GEORGE HARDEN, OF TOLEDO, OHIO.

ACETYLENE-GAS APPARATUS.

SPECIFICATION forming part of Letters Patent No. 634,817, dated October 10, 1899.

Application filed December 28, 1898. Serial No. 700,518. (No model.)

To all whom it may concern:

Be it known that I, GEORGE HARDEN, a citizen of the United States, residing at Toledo, in the county of Lucas and State of Ohio, have 5 invented new and useful Improvements in Acetylene-Gas Apparatus, of which the following is a specification.

My invention relates to apparatus for making acetylene gas; and it consists in the peculiar and advantageous construction hereinafter described, and particularly pointed out in the claims appended.

In the accompanying drawings, Figure 1 is a longitudinal vertical section of my improved apparatus. Fig. 2 is a horizontal section taken in the plane indicated by the line 2 2 of Fig. 1. Fig. 3 is an enlarged detail section taken in the plane indicated by the line 3 3 of Fig. 1. Fig. 4 is an enlarged detail view of a swinging spout for discharging water into the carbid-holder.

In the said drawings similar letters designate corresponding parts in all of the several views.

25 My improved apparatus comprises a reservoir A and a gas-generator B, mounted upon a common base C and connected together, as hereinafter described. The reservoir A is surrounded at its upper end by a water-belt D and is provided with a pipe E, which leads from a point adjacent to the top of the reservoir through the bottom thereof and has for its purpose to convey gas to the several distributing-pipes (not shown) of a building.

30 The generator B is of the construction best shown in Fig. 1—that is to say, it comprises a central receptacle a, a water-jacket b, extending entirely around and below the receptacle and having its upper wall c inclined inwardly and downwardly to facilitate the placing of the carbide-holder in receptacle a, a water-belt d, and a removable cover e, having a depending annular flange f, designed to take into the water in belt d and form a seal, and also having hasps g, designed to take over staples h and be secured thereon by locks (not shown) to prevent unauthorized persons from opening the generator while the same is in operation. The carbide-holder F in the receptacle a is of the removable type and is provided with a central vertical foraminated tube

i, having a flared mouth j at the upper end thereof, as shown.

G is a gasometer arranged in the reservoir A and sealed by the water therein. It is 55 guided in its vertical movements by headed rods k, movable in guides l on the reservoir, and is provided with a pocket m on its top and also with interior pockets n for the reception of weights, the purpose of which is to 60 retard the elevation of the gasometer. The interior pockets n are advantageous, because unauthorized persons are prevented from meddling with the weights, and when desired they alone may be employed, the top pocket m being dispensed with. 65

H is a pipe for conveying water from the reservoir A to the jacket b of the generator, and I is a pipe for conveying the water from said jacket back to the reservoir. The water 70 entering the jacket b of the generator at the bottom thereof tends to reduce the temperature therein, and when heated rises and passes through the pipe I back to the reservoir, thus giving place to fresh water from the reservoir 75 and maintaining a constant circulation of water through the jacket b while the apparatus is in operation, with the result that the temperature in the generator is maintained at about 112° Fahrenheit, which is an important 80 advantage.

J is a pipe for conveying water to the calcium-carbide holder F. This pipe J terminates at its inner end in a spout K and at its outer end in a vertically-disposed portion L, 85 which loosely receives a pipe M, depending from a sight-glass N, as best shown in Fig. 3. The sight-glass N is arranged in a casing P, which is connected by a bracket P' to the gasometer and is equipped with a stop-cock 90 Q (see Fig. 3) and is connected in turn by a flexible pipe or hose R with the water-belt D at the upper end of the reservoir. By virtue of this construction the pipe M, sight-glass N, and the casing P thereof are free to rise 95 and fall with the gasometer without affecting the supply of water to the carbide-holder F, except when the sight-glass is raised above the water in belt D. When the sight-glass is thus raised above the water in the belt D, the 100 supply of water to the carbide-holder is shut off until a portion of the gas in the gasome-

water is removed therefrom and the said gasometer descends sufficiently to carry the sight-glass below the water in belt D, when the supply of water to the carbid and the generation of gas will be resumed. It will also be observed that the sight-glass N enables the attendant of the apparatus to perceive when water is being fed to the carbid-holder, which is a very desirable feature.

10 S is a pipe for conveying gas from the generator to the gasometer. This pipe S leads from the upper portion of the generator down through the bottom of the same and thence to and through the bottom of the reservoir 15 and up to a point well above the water-level therein. At about the point shown the pipe S is provided with a three-way cock T, with which is connected a pipe U, which extends up in the reservoir A to a point above the water-level therein, as shown in Fig. 1. From an intermediate point of this pipe U leads a pipe V, which extends outside the building in which the apparatus is situated and is designed to carry off gas, as will be presently 25 described.

20 W is a tube which is connected to the top of the gasometer and loosely receives the pipe U. This tube W is provided at about the point shown with apertures p, which are designed when the gasometer is raised sufficiently to carry them above the level of the water in the reservoir to permit the gas to pass into the pipe U and escape by way of the pipe V into the open air. The gasometer 35 will only be raised to the extent stated by a dangerous pressure of gas, and hence it will be seen that the pipes U V and the tube W serve the important purpose of lessening the liability of an explosion.

40 In order that an explosion of gas may be avoided in the event of a fire in the building where the apparatus is located, I have provided the pipe V', between the house-supply pipe E and the blow-off pipe V, and a valve 45 V² in said pipe V'. The valve V² is normally closed; but in the event of fire it is designed to be opened. When said valve is opened, the gas in the gasometer and the several supply-pipes of the building is discharged through 50 the blow-off pipe V, and in consequence an explosion of gas is avoided.

The three-way cock T is normally set to establish communication between the generator and gasometer and shut off communication between the pipe S and the pipe U. When, however, it is desirable to discharge the generator of gas, the cock T is turned to establish communication between the pipes S and U.

With a view of permitting of the generator 60 B being opened and the carbid-holder being replenished without subjecting the operator to discomfort and filling the building wherein the apparatus is located with gas I have provided a normally-closed cock t in the generator 65 tor-cover e, an opening u in the removable cover v of the carbid-holder, a self-closing valve w for closing said opening, and a lug x

on the cover e designed to engage a corresponding lug y on the spout K. The spout K is connected to swing in a vertical plane and 70 has a depending portion z designed to take through the opening u in the cover v of the carbid-holder. With the parts just described in the positions shown in Fig. 1 the depending portion z of spout K impinges against valve w 75 and against the action of the weight a' of said valve holds the same away from its seat and permits gas to escape from the carbid-holder through opening u into the interior of the generator. 80

When it is desired to open the generator and replenish the carbid-holder, the cock T is turned to establish communication between the pipes S and U and an air-pump is connected to the cock t, after which said cock is 85 opened. With this done the air-pump is actuated, and in consequence the gas in the generator is forced out through the pipes S, U, and V. While the air-pump is being actuated the cover e of the generator is raised sufficiently to withdraw the spout K from the opening u and is held in such position a short time, after which it is entirely removed. As soon as the spout K is raised out of the opening u the weight a' of the valve will close the same and prevent the passage of gas from the carbid-holder to the generator. From this it follows that when the cover e is removed from the generator after the manner described the carbid-holder is sealed and all gas is discharged from the generator, and in consequence the dissemination of gas throughout the building is prevented and the operator is not subjected to discomfort. The sealed carbid-holder may be removed to the open air 105 and there replenished and may then be returned to its position in the generator. When the cover e of the generator is replaced in position, the spout K entering the opening u in the cover of the carbid-holder will press the valve w away from its seat, and thereby establish communication between the said holder and the generator.

It is obvious that prior to the removal of the cover e the cock Q should be closed to cut 115 off the supply of water to spout K and that said cock should be opened as soon after the cover e is replaced in position as it is desired to reestablish the generation of gas.

Water may be supplied to the reservoir A 120 and belt D by any suitable means. I prefer, however, to employ supply-pipes r s.

The operation of my improved apparatus, briefly stated, is as follows: Water is conducted from the belt D to the spout K and is 125 discharged by the latter into the tube i of the carbid-holder, by which it is distributed to the mass of carbid throughout the height thereof. This results in the generation of acetylene gas, which is conveyed by the pipe 130 S to the gasometer G. As the generation of gas progresses the generator becomes heated, and in consequence the circulation of water from the reservoir to the jacket b of the gen-

erator and thence back again to the reservoir is established and maintained, with the result that the temperature in the generator is prevented from becoming too high. The generation of gas continues until the gasometer is raised sufficiently high to cut off the supply of water from the spout K, when it ceases. Gas is removed from the gasometer through the pipe E, and when a sufficient quantity is taken out to enable the gasometer to descend the supply of water to the spout K will be re-established and the generation of gas resumed until the gasometer is again raised sufficiently to cut off the supply of water to spout K.

15 The apparatus described, while very simple and inexpensive, is highly efficient in operation and is calculated to maintain the temperature in the generator at about 112° Fahrenheit when working full capacity, which is an important advantage. It will also be observed that by reason of the construction described the generation of gas is automatically stopped when a certain quantity of gas is contained in the gasometer and is automatically started when an appreciable quantity of gas is removed from the generator; also, that when an overproduction of gas takes place and the pressure becomes too great the surplus will be automatically discharged and the danger of an explosion obviated. From this it follows that my improved apparatus requires but little attention, which is an important and material advantage.

Having thus described my invention, what I claim is—

35 1. An acetylene-gas apparatus comprising a generator, a reservoir, a gasometer arranged in the reservoir and sealed by the water contained therein and having a depending tube provided with an escape-opening, a gas-conveying pipe leading from the generator into the reservoir and extending above the level of the water in the latter and having a three-way cock, a safety discharge-pipe leading 40 through the bottom of the reservoir and loosely entering the tube of the gasometer, a connection between said pipe and the three-way cock, a house-supply pipe leading from the interior of the gasometer, a pipe interposed between and connecting the safety discharge-pipe and the house-supply pipe, and a valve in said interposed pipe, substantially as specified.

50 2. An acetylene-gas apparatus comprising a generator, a reservoir, a gasometer arranged in the reservoir and sealed by the water con-

tained therein and having a depending tube, a safety discharge-pipe loosely entering the tube of the gasometer, a house-supply leading from the interior of the gasometer, a pipe 60 interposed between and connecting the safety discharge-pipe and the house-supply pipe, and a valve in said interposed pipe, substantially as specified.

3. In an acetylene-gas generator, the combination of a casing, a carbid-holder removably arranged therein and having an opening and a self-closing valve for said opening, and a movable spout connected with a source of water-supply; said spout being arranged to 70 enter the opening of the carbid-holder and unseat the valve controlling said opening, substantially as specified.

4. In an acetylene-gas generator, the combination of a casing, a carbid-holder removably arranged therein and having an opening in its cover and a self-closing valve for said opening, a water-supply conduit arranged at one side of the carbid-holder, a vertically-movable spout connected to said conduit and arranged to enter the opening of the carbid-holder and unseat the valve controlling said opening, a cover for the generator, and means whereby when the cover is raised the spout will also be raised, substantially as specified. 85

5. In an acetylene-gas generator, the combination of a casing having a water-belt at its upper end, a carbid-holder removably arranged in said casing and having an opening in its cover and a self-closing valve controlling said opening, a water-supply conduit arranged at one side of the carbid-holder, a vertically-movable spout connected to said conduit and arranged to enter the opening of the carbid-holder and unseat the valve controlling said opening, a cover for the generator having a depending flange arranged to enter the water-belt of the generator-casing, coacting devices on said cover and the spout whereby when the cover is raised the spout will also 100 be raised, a gas-conveying pipe connected with the interior of the generator, and a cock also connected with the interior of the generator and adapted for the connection of an air-pump, substantially as specified. 105

In testimony whereof I have hereunto set my hand in presence of two subscribing witnesses.

GEORGE HARDEN.
